SHROUD RING

Louis Landweber, Bethesda, Md.

Application November 30, 1942, Serial No. 467,477

6 Claims. (Cl. 114—235)

(Granted under the act of March 3, 1883, as
amended April 30, 1928; 370 O. G. 757)

Specifically, this invention is a shroud ring or the like with circumscribed crossed fins and means for securing the same in place.

In some marine operations, it is desired to tow a long cylindrical body, as a hawser or cable, in the direction of its length, and at a substantially constant distance below the water surface.

In a towing operation of the nature mentioned, difficulty is encountered in maintaining the body in its desired horizontal condition. The forward end thereof may readily be depressed to the proper depth, but the free end will rise toward the surface or sink below the horizontal, its direction depending upon whether the body has positive or negative buoyancy.

This invention is applied at spaced intervals along the towed body, every twenty feet, for example; and the device function to maintain the body at nearly a constant depth throughout its length.

The principal object of the invention is to provide a shroud ring and guiding fins or vanes, together with clamping means for rapidly and readily applying the device to and removing it from the body for which it is intended.

Other objects will appear from the following specification and claims.

In the drawing:

Figure 1 is a vertical section taken through the center of the shroud ring and vanes of this invention.

Figure 2 is a detail of securing means used on the ring; and Figure 3 is a perspective view of the ring and vanes in place on a cylindrical body.

Referring to the drawing, 10 is the shroud ring proper of the invention. The ring is split, and one end portion 11 is provided with a slot 12. The other end portion 13 is cut away at its edges to form a tongue 14, the width of which approximates the width of slot 12. The end of the tongue is bent beneath itself to form a hook 15.

On the interior of the ring are secured two substantially identical members, which may be seen in Figures 1 and 3. One of these comprises an arcuate portion 16, a radial fin or vane 17 with a bent lip 18, and another radial fin 19 with a lip 20. The lips 18 and 20 are so bent as to conform to the curvature of the ring 10. The other member consists of the central portion 21, a fin 22 and lip 23, and a fin 24 and lip 25. These members may be fastened to the ring in any desired manner. As shown, they are secured by means of screws 26, each of which passes through the ring 10 and through one of the lips 18, 20,

23 and 25. Cooperating nuts 27 are provided for the screws.

The arrangement of the parts should be such that when the ring 10 is closed, as in Figures 1 and 3, the fins or vanes are located along mutually perpendicular diameters of the ring.

Further, the break in the ring must provide access to the center of the ring, and it is therefore apparent that neither of the fin members may straddle the break.

The sizes and proportions of the parts will of course vary with the intended application of the invention. As may be seen from the drawing, the hook 15 is adapted to fit into the slot 12 of end portion 11. The arcuate sections 16 and 21 should be of such a radius, and the vane members 17, 19, 22 and 24 should be of such length, that the cylindrical body to which the device is attached (as 30, Figure 3) will be firmly clamped when the ring is closed. The parts must be somewhat compressed in order that the hook 15 may engage the slot 12. Commonly the cylindrical member itself will be somewhat compressible; but, in any event the ring and its internal members may be made of relatively thin, elastic material which can be distorted enough to put the device in place, and which will then revert to desired shape.

Preferably the end 13 of the ring 10 is offset somewhat, as indicated at 28. This offset provides a better connection between the two ends of the ring, since the offset is approximately the depth of the thickness of the ring, and is spaced from the end of the hook 15 about the distance of the slot 12 from the end of the part 11.

The device is put in position by opening the ring and placing it over the cylindrical body for which it is intended so that the same is clasped by the arcuate segments 16 and 21. The ends of the ring are then forced together and the hook 15 is engaged in the slot 12.

The above description has been confined to the embodiment of the invention illustrated in the drawing. Obviously changes can be made within the spirit of the invention over the structure described and shown, and it is to be understood, therefore, that the invention includes everything that properly falls within the scope of the appended claims.

The invention herein described and claimed may be manufactured and/or used by or for the Government of the United States of America without the payment of any royalty thereon or therefor.

I claim:

1. A shroud ring or the like adapted to be applied to a cylindrical body, comprising means for clasping said body, radial fins extending outwardly from said means, a split shroud ring proper surrounding said means and said fins and supported by the latter and adapted when closed to compress said means.

2. A shroud ring or the like adapted to be applied to a cylindrical body, comprising means for partially encircling the cylindrical body, fins secured to said means and extending outwardly therefrom, a split shroud ring proper surrounding said means and said fins and supported by the latter, and means for securing together the ends of the split ring to compress said means and to align said fins on mutually perpendicular diameters of the closed ring.

3. A shroud ring or the like adapted to be applied to a cylindrical body, comprising a plurality of members for clasping said body, fins secured to said members and extending outwardly therefrom, a split shroud ring proper surrounding said members and said fins and supported by the latter, and means for securing together the ends of the split ring to compress said member and to align said fins on mutually perpendicular diameters of the closed ring.

4. A shroud ring or the like adapted to be applied to a cylindrical body, comprising two arcuate segments for partially encircling said cylindrical body, a radial fin secured to each extremity of each of said segments and extending outwardly therefrom, a split shroud ring proper surrounding said segments and secured to the radial fins, and means for securing together the ends of the split ring to compress said segments and to align said fins on mutually perpendicular diameters of said ring.

5. A device for attachment to a tow cable comprising a resilient split sleeve for disposition in spaced coaxial relation to the cable, a plurality of cable clamp members, and radial fins connecting the clamp members to the sleeve and urging the clamp members into engagement with the cable upon closing of the split sleeve.

6. A device for attachment to a tow cable comprising a resilient split sleeve disposable in spaced coaxial relation to the cable, a plurality of cable clamp members, each including a cylindrical segment and at least one fin extending between the segment and the sleeve, said fins urging the cylindrical segments into engagement with the cable upon closing of the split sleeve.

LOUIS LANDWEBER.
